SOFA BEDSTEAD

Antonio T. Pison, Molo, Iloilo, P. I.

Application November 27, 1935, Serial No. 51,919

2 Claims. (Cl. 5—40)

The invention relates to a bedstead and more especially to a sofa bedstead.

The primary object of the invention is the provision of an article of furniture of this character, wherein the construction thereof is such that the said article can be utilized either as a sofa or a double bedstead, the structure of the said article being novel in form so that the converting of such article may be had with dispatch and without labor on the part of the operator thereof.

Another object of the invention is the provision of an article of furniture of this character, wherein the same permits of the storing of bedding material, such as pillows, covering and other decorative accessories and the converting of the article for service as a sofa or as a bedstead is easily accomplished and in either service is neat and attractive in appearance.

A further object of the invention is the provision of an article of furniture of this character, wherein through the use of latches when the article is converted into a sofa or a bedstead it will be firm and secure and when in service as a bedstead may wear a canopy of mosquito netting so as to protect the occupant or occupants from flying insects, particularly mosquitoes.

A still further object of the invention is the provision of an article of furniture of this character, which is comparatively simple in construction, thoroughly reliable and efficient in operation, strong, durable and inexpensive to manufacture and install.

With these and other objects in view, the invention consists in the feature of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a vertical longitudinal sectional view through an article of furniture constructed in accordance with the invention showing it carrying a canopy of mosquito netting.

Figure 2 is a bottom plan view.

Figure 3 is an end elevation.

Figure 4 is a top plan view with the rest frame removed and the article of furniture converted into a sofa.

Figure 5 is a side elevation of the article of furniture serving as a bedstead.

Figure 6 is a view similar to Figure 5 looking toward the opposite side thereof and showing by dotted lines the shifted position of the head and

foot pieces for converting the article from a bedstead to a sofa.

Figure 7 is a bottom plan view of the rest frame for the article of furniture.

Figure 8 is a vertical transverse sectional view through the article of furniture when converted into a sofa.

Figure 9 is a fragmentary enlarged vertical sectional view taken transversely of the article of furniture when in position as a bedstead.

Figure 10 is a sectional view on the line 10—10 of Figure 9 looking in the direction of the arrows.

Figure 11 is an enlarged fragmentary vertical sectional view showing in detail one of the latches 15 of the article of furniture and taken on the line 11—11 of Figure 2.

Figure 12 is an elevation of one of the supports for the canopy of mosquito netting for the article.

Figure 13 is a sectional view on the line 13—13 of Figure 12.

Figure 14 is a vertical transverse sectional view through a rest frame of modified form.

Similar reference characters indicate corresponding parts throughout the several views in the drawings.

Referring to the drawings in detail, the article of furniture comprises a combined sofa and bedstead including head and foot pieces A and B, respectively, these being of the open railed type and each has stationary and horizontally swinging sections 10 and 11, respectively. Between the stationary sections 10 of the head and foot pieces A and B is a box-like body 12 provided with slide drawers 13 and a compartment 14 therebetween. This compartment 14 is accessible on the swinging open of a door 15 thereto, it being vertically swung upon hinges 16 and carries a latch 17. The box-like body 12 is made secure to the head and foot pieces in any desirable manner and the said body is made up of boards. The compartment 14 is for the storage of bed clothing or accessories while the drawers 13 are suitable for carrying night garments, slippers or other wearing apparel.

It is preferable to have the head and foot pieces A and B provided with intermediate and outer legs or feet 18 and 19, respectively. The box-like body 12 is substantially the width of the sections 10 of the head and foot pieces A and B and the sections 11 are swingingly supported by upper and lower hinges 20 and 21, respectively, the lower hinges having their pintles out of vertical alignment with the pintles of the upper 55

hinges 20 so that when these sections 11 are swung inwardly against the box-like body 12 the leading ends will slightly rise from a horizontal plane when the said sections 10 and 11 are in alignment 5 with each other, this being the position thereof when the article of furniture is serving as a bedstead. When the sections 11 are swung inwardly against the box-like body 12 they are in a position for the servicing of the article of furniture 10 as a sofa, these services being described herein-after in detail.

Adapted to be superimposed upon the box-like body 12 to lie at rest upon resilient corner pads 22 is one of a pair of swinging sections 23 constituting a rest frame C for a mattress, cushions or the like, these sections 23 being swingingly connected by hinges 24 and the other of said sections 23 when lowered into the same plane with its companion section of the frame C will extend between 20 the sections 11 of the head and foot pieces A and B when these sections 11 are aligned with the sections 10 of said pieces so that the rest frame will be positioned for the servicing of the article of furniture as a bedstead. The sections 11 carry 25 at their leading ends lateral bearings 25, these having upstanding pins 26 and side keeper lugs 27, respectively, so that the section 23 when between the sections 11 may be made secure by having the pins 26 enter sockets 28 companion thereto 30 in the frame C, the latter being also provided with leaf spring catches 29 for latching engagement with the lugs 27 and thus fastening the frame C with the bearings 25, the frame C being adapted to rest upon the box-like body 12 and the said 35 bearings 25 when the article of furniture is serving as a bedstead.

The head and foot pieces A and B are equipped with leaf spring latches 30, these being carried by the sections 10 of said pieces and are engageable 40 in seats 31 provided in the sections 11 of said pieces so as to hold the said sections 11 in fastened aligned relation to the sections 10.

Within the box-like body 12 at the proper location are spring thrown latching bolts 32, these 45 being preferably within the compartment 14 and operate vertically to extend through the top of said box-like body 12 for engagement with the bearings 25 when the sections 11 are manually swung inwardly against the back or innermost 50 side of the said body 12 for latching the same in this position, the said sections 11 being initially moved inwardly under the action of coiled retractile springs 33 anchored to said sections 11 and to the body 12 in any suitable manner. The 55 bolts 32 are fitted with inverted substantially L-shaped arms 34 which play through suitable clearances 35 in the back or innermost side of the body 12 and are passed through an upper rail 35'. These arms are connected to links 36 constituting 60 hangers beneath the rail 35' for a foot rail 37 suspended outside of the box-like body 12 and foot controlled. Beyond opposite ends of the rail 37 are trips 38 each including double companion levers and the same are acted upon by the said 65 rail 37 which has its ends in an overlapped relation to said trips so that when depressing this rail 37 the trips will play upon the push pins 39 slidably fitted vertically in the sections 11 to cause such pins to operate the latches 30 for automatically releasing such latches and thus freeing the 70 sections 11 at these points. These sections 11 when swung outwardly under the tension of the springs 58 are latched in the outward position aligned with the sections 10. Now the latches 75 fastening the sections 11 in their full outward

position are released by depressing the foot rail 37 and such sections are moved slightly inwardly by the springs 33 to avoid relatching when the pressure is relieved from the said foot rail. The sections 11 are moved inwardly against the resistance of the springs 58 and when folded against the body of the structure they are latched in this position. Thus it is immaterial as to the length of the bedstead because it is not necessary that an operator swing the sections outwardly when 10 depressing the rail 37 because when these sections 11 are released from their inwardly folded position, the springs 58 are active to move the same outwardly while such sections 11 after initial movement by the springs 33 are manually shifted 15 inwardly to folded position. This foot rail 37 also releases the latching bolts 32 when engaging the bearings 25 so that the sections 11 can be free to permit the same to be brought into alignment with the sections 10 or for the swinging of said 20 sections 11 inwardly against the box-like body 12.

The frame C in the sections 23 thereof has diagonal braces 40 and it is also preferable to have this frame carry rattan fabrication 41 although the same may be cane fabrication and upon this 25 frame C is accommodated the cushions or a mattress when the article of furniture is converted into a bedstead or sofa. The section 23 of the frame C is adapted to extend between the sections 11 of the head and foot pieces when the 30 latter are unfolded to align with the sections 10; this section 23 when swung upwardly rests against these sections 11 when folded to constitute a back to the sofa when the article of furniture is converted into the same.

The frame C has the section 23 adapted to be disposed between the sections 11 of the head and foot pieces fitted with brackets 42 constituting a rack for the uprights 43 and cross head bows 44 therefor which when set up afford a support 40 for mosquito netting 45 serving as a canopy. The uprights 43 when in use are detachably fastened at 46 and 47, respectively, to the head and foot pieces A and B. One of the uprights has fitted 45 therein electric wiring 48 for a light bulb 49, the electric current being controllable by a switch 50 upon said upright, the switch being conveniently located to an occupant of the article of furniture either as a sofa or a bedstead and likewise the electric light bulb 49 being suitably 50 located for reading purposes. The section 23 of the frame C to be superimposed upon the box-like body 12 is equipped with a padding or cushioned at 51 for comfort when the article of furniture is converted from a bedstead into a sofa.

The drawers 13 and the door 15 are located at the front or outermost side of the box-like body 12 for convenient access and the outer faces of these are flat and smooth so as not to detract 60 from the article of furniture when serving as a bedstead or sofa.

In Figure 14 of the drawings there is shown a slight modification of rest frame wherein the sections 52 and 53, respectively, include the tongue and grooved joined boards 54 bolted or otherwise made secure to angled bars 55 marginally about said frame. The angled bars 55 enable the seating of a mattress (not shown) upon this frame when covering the sections 52 and 53 thereof. It may be found desirable to have the section 23 of the frame C constituting the back to the sofa when the article of furniture is converted 70 rest upon shoulders 56 carried by the sections 10 of the head and foot pieces A and B instead 75

of resting against the inwardly folded sections 11 of these pieces.

The uprights 43 have connection with the bows 44 by couplings 57 when these parts are set up to function as a canopy for the netting 45 which is hung over the article of furniture when converted into a bedstead for protecting the occupant or occupants from mosquitoes or other flying insects. The uprights 43 are readily separable from the head and foot pieces A and B when the mosquito netting 45 is not to be used and the bows 44 separated from the uprights 43 so that these parts can be stored or engaged in the rack 42 as hereinbefore set forth and in the knocked-down or stored condition are hidden from view when the article of furniture is used as a sofa or bedstead, the said parts being readily removable from the rack when required for use.

The lower hinges 21 carry coiled springs 58 which are for the purpose of swinging the sections 11 outwardly while the springs 33 give inward starting action to these sections when released by the catches 30 for the manual inward folding of said sections 11. In other words, the tension of the springs 33 at the beginning of the folding or swinging movement of the sections 11 is greater than the tension of the springs 58 in the hinges 21. The springs 33 become inactive and slacken instantly on the moving inwardly of the sections 11 while the springs 58 concurrently are active thus there being no possibility of the catches 30 reseating at 31 when released by the foot rail 37 because the instant the catches are unseated the sections 11 begin to swing inwardly from aligned matched relation to the sections 10 of the head and foot pieces A and B.

What is claimed is:

1. An article of furniture of the character de-

scribed comprising head and foot pieces each including stationary and horizontally swinging sections, a box-like body supported by the stationary sections and arranged between the same, a rest frame carried by the box-like body and having an extensible portion for extension between the swinging sections of the head and foot pieces, means for initially moving the swinging sections of the head and foot pieces inwardly toward the box-like body for subsequently holding the extensible portion of the rest in a position to form a back support and foot operated means for latching the swinging sections of the head and foot pieces in positions when the rest frame is extended therebetween and when the latter is in back supporting position.

2. An article of furniture of the character described comprising head and foot pieces each including stationary and horizontally swinging sections, a box-like body supported by the stationary sections and arranged between the same, a rest frame carried by the box-like body and having an extensible portion for extension between the swinging sections of the head and foot pieces, means for initially moving the swinging sections of the head and foot pieces inwardly toward the box-like body for subsequently holding the extensible portion of the rest in a position to form a back support, foot operated means for latching the swinging sections of the head and foot pieces in positions when the rest frame is extended therebetween, means for releasably latching the swinging sections of the head and foot pieces when moved against the box-like body, corner pads carried by the box-like body for the said rest frame and means for latching the rest frame with the sections of the head and foot pieces when said frame is extended therebetween.

ANTONIO T. PISON.
